INCINERATOR

Robert E. Zahn, Milwaukee County, Wis.

Application February 15, 1950, Serial No. 144,230

22 Claims. (Cl. 110—18)

1

This invention relates to improvements in incinerators and more particularly to the provision of an incinerator embodying a minimum number of parts of simple structural form which may either be shipped in knocked-down condition and easily assembled by the purchaser or be preassembled and shipped to provide an inexpensive rigid gas tight unit of neat appearance and large capacity, and which will occupy a minimum of floor space.

A primary object of the invention resides in the provision of corner castings of novel construction having means for positioning courses of fire-brick in vertically aligned relation to form the combustion chamber side walls of the incinerator, together with adjustable tie rods connecting diagonally opposite corner castings at their upper and lower ends to tightly bind said castings against the ends of the fire-brick.

A further important object of the present invention resides in the provision of a knock-down, grateless incinerator structure having novel metal skeletonized corner frame elements provided with vertically arranged air inlet ports to apply the "air torch" method of combustion, and front charging door, front ash door, and top flue connection castings adapted to cooperate with diagonally disposed tie rods to connect said corner frame elements together to receive and maintain built-up, mortarless, fire-brick combustion chamber walls in assembled relation.

Another object of this invention is to provide reinforcing uprights for the combustion chamber walls designed to overlap the abutting ends of adjacent courses of fire-brick to prevent inward buckling of the combustion chamber fire walls, particularly in event of shipment of preassembled units.

A further object is to provide charging and ash door frames assembled between and rigidly bolted to the front corner castings, together with a separate top casting having provision for the connection of an outlet flue and adapted to be bolted to the charging door frame and the rear corner castings.

An additional object of the invention is to provide an incinerator structure in which fire-brick are also assembled between the vertically spaced door frames together with an outer facing sheet of hard asbestos between said frames and the fire-brick, and similar facing sheets between the corner castings covering the outer faces of the side and rear fire-brick walls of the incinerator.

Another object of the invention resides in the provision of vertically spaced openings extending

2

through certain of the corner castings to insure the supply of air in adequate volume to the interior of the incinerator for the complete and rapid combustion of the garbage and other refuse material placed therein.

With the above and other objects in view, the invention comprises the improved incinerator and the construction and relative arrangement of its several parts as will hereinafter be more fully described, illustrated in the accompanying drawings and subsequently incorporated in the subjoined claims.

In the drawing, wherein there are illustrated practical embodiments of the invention and in which similar reference characters designate corresponding parts throughout the several views:

Figure 1 is a front elevation of a preferred form of the improved incinerator of the present invention;

Figure 2 is a vertical sectional view taken substantially on the line 2—2 of Figure 1;

Figure 3 is a horizontal section taken substantially on the line 3—3 of Figure 1;

Figure 4 is a top plan view before final completion of the assembly by attachment of the top closure plate;

Figure 5 is a fragmentary horizontal sectional view taken substantially on the line 5—5 of Figure 1;

Figure 6 is a detailed horizontal section through one of the front corner castings and adjacent fire-brick walls taken substantially on the line 6—6 of Figure 1;

Figures 8 and 9 are detail sectional views taken substantially on the lines 8—8 and 9—9 respectively of Figure 4;

Figure 10 is a detail vertical section on the line 10—10 of Figure 4 illustrating the connection of one of the top tie rods to one of the front corner castings;

Figure 11 is an elevational view on an enlarged scale of one of the corner castings;

Figure 12 is a longitudinal sectional view taken substantially on the line 12—12 of Figure 11;

Figure 13 is a top plan view of the corner casting of Figure 11;

Figure 14 is a horizontal sectional view taken on the line 14—14 of Figure 12;

Figures 15, 16 and 17 are similar horizontal sectional views taken on the lines 15—15, 16—16 and 17—17 respectively of Figure 12;

Figure 18 is an exploded perspective view of

one of the front corner castings and the charging and ash door frames secured to the other front corner casting;

Figure 19 is a perspective view of the improved incinerator structure in partially assembled condition.

Figure 20 is a detail fragmentary elevation of a means for strengthening the side walls of incinerator combustion chamber of large capacity;

Figure 21 is a horizontal section taken substantially on the line 21—21 of Figure 20;

Figure 22 is a fragmentary vertical section illustrating a slightly modified embodiment of the incinerator; and

Figure 23 is a detail horizontal section taken substantially on the line 23—23 of Figure 22.

Referring in further detail to the drawings, the body of the incinerator comprises four identical castings 10, upper and lower charging and ash pit door frames 12 and 14 respectively, disposed between and rigidly connected to the front corner castings 10, a top casting assembly 16 rigidly connected to the door frame 12 and to the rear corner castings 10, and combustion chamber walls of a fire-brick assembled between and rigidly fixed in position by the corner castings 10.

The corner castings 10 are of the same general form and construction. As shown in Figures 11 to 17 inclusive, each of these castings has a body portion 18 which is generally of arcuately curved form in cross section providing side flanges 20 extending throughout the length thereof at an angle of substantially 90 degrees to each other. When in its assembled position the convex surface of the body wall 18 of said castings faces outwardly and this wall, between the side flanges 20 is formed to provide a trough or channel 22 terminating in spaced relation from the opposite ends of the casting and interrupted at vertically spaced points by the horizontal webs 24. The side walls 26 of this trough or channel are disposed substantially at right angles to the flanges 20 of the casting and the base wall of the trough is formed on the inner side of the casting with a longitudinally extending rib 28 provided with relatively thick portions or bosses 30 at vertically spaced points. Air inlet openings 32 extend inwardly and downwardly through the bosses 30. They are preferably provided in both the front and rear corner castings 10 and adapt the incinerator of this invention for operation in accord with the so-called "air torch" principle of combustion which effects a burning of the contents from the top downward and eliminates the need for grates and assures adequate air for combustion whether the incinerator is full or only partially full.

Passages 32 for the small incinerator, as illustrated in Figures 1 through 19 of the drawings, are all arranged at approximately a 15° downward inclination toward the geometrical center of the combustion chamber. Each corner casting is provided with seven equally vertical spaced passages. The combined volumetric capacity of these passages is substantially less than the capacity of the flue connection. As a consequence, when the incinerator is connected to a suitable chimney flue the air is injected into the combustion chamber through passages 32 at high velocity and sweeps downwardly through the entire area of the combustion chamber before escaping through the flue connection. This injection of air not only assures vigorous and complete combustion during firing periods but

also causes the air to penetrate deeply into the mass of refuse to be burned thereby effecting a preliminary dehydration of any wet refuse. This dehydration function continues even during non-firing periods, unless the flue damper is closed, due to the normal chimney flue action.

As the cross-sectional dimensions of the incinerator are increased, it has been found desirable to change the axial direction of certain of the passages or to alter the shape of the discharge end of the passages 32 to assure sweeping of the entire incinerator area with air. For example, alternative vertical passages may be inclined away from the center and slightly toward the adjacent side walls or the discharge end of the passages may be given a fan shape to spread the ejected air stream over a widened area. Either of these changes will produce the desired result and assure vigorous and complete combustion and suitable dehydration even in larger sized incinerators.

The corner castings below the upper end thereof are each formed with a flange 34 projecting inwardly from the body wall thereof and integrally connected with the upper end wall of the trough 22 to provide a supporting seat for the top casting assembly 16 when they are used as rear corner castings. This flange has a lug or extension 36 (Figures 12 and 13) provided with an opening 38 to receive a long stove bolt 40 whereby the top casting assembly 16 is rigidly connected to the corner castings 10.

Each corner casting at its extreme upper end is further provided on the inner side of the body wall 18 with a boss 42 and a tie rod receiving opening 44 extending horizontally therethrough. A vertical tapped opening 46 of relatively small diameter intersects the opening 44 at the upper side thereof for a purpose to be presently pointed out.

At its lower end, each corner casting 10 has vertically spaced horizontally disposed flanges 48 projecting inwardly from the body wall 18 thereof, and said wall, adjacent to and above flange 48 is provided with a tie rod receiving opening 50. Side flanges 20 of each front corner casting 10 are provided with vertically spaced openings 52 adapted to receive stove bolts 54 for rigidly securing the door frames 12 and 14 to said corner castings as seen in Figure 3 of the drawings. Since the openings 52 are not used to secure frames 12 and 14 in place are covered by the overlapping edges of the exterior finish panels, the presence of these unused openings is in no way objectionable.

The charging door frame 12 is formed with an inwardly turned hollow bead 56 along its upper edge in partially overlying, vertically spaced relation to a relatively wide top flange 58. A plurality of spaced vertical webs 60 reinforce bead 56 and flange 58 to impart rigidity thereto and provide spaced seats for the top closure plate to be hereinafter described.

As shown in Figures 2 and 4 of the drawings, the top casting assembly 16 comprises a rectangular section 62 having marginal upstanding flanges 64. The two rear corners of this casting are formed at an angle of substantially 45 degrees so as to seat upon the flanges 34 of the rear corner castings and not interfere with the upstanding corner casting wall section bearing boss 42. The flanges are notched as shown at 66 in Figure 7 to receive the tie rods when it becomes necessary to raise casting 62 sufficiently to permit insertion of the top course of brick

and the asbestos strip between casting 62 and the top course of brick.

Section 62 of the top casting near its rear edge is also provided with a flue opening defined by an upstanding cylindrical neck 68 to which a flue pipe for the incinerator is adapted to be connected. Diagonally disposed reinforcing webs 70 integrally connect the wall of the neck 68 with the marginal flanges 64 of the casting. Additional spaced parallel webs 72 extend forwardly from the neck 68. These webs are integrally joined with the front flange 64 and together with the lower wall of section 62 define a pocket 73 for a purpose to be hereinafter pointed out. The casting section 62 is also formed along the lower front edge thereof with a projecting flange 74.

A separate relatively narrow casting section 76 completes the top casting and has one of its ends disposed between webs 72. This end of casting section 76 is rigidly secured to the casting 62 by 10 spaced stove bolts 78. The other end of the casting 76 is connected to the center of the top flange 58 of the charging door frame 14 by stove bolt 80 positioned through a slot 82 in said flange. Casting 76 is also formed with a plurality of upstanding webs forming sand receiving pockets and is provided along each longitudinal side edge with a laterally projecting flange 84. Adjacent to its rear edge and parallel therewith, the top casting 62 is provided with a depending flange 86 15 for a purpose which will be later explained.

The upper ends of diagonally opposite corner castings 10 are connected by the tie rods 88, said rods being inserted through the openings 44 in the respective corner castings and extending over 20 the top casting sections 62 and 76. Each tie rod at one end is threaded to receive an adjusting nut 90 bearing against the outer convex surface of one corner casting while the other end of the tie rod is formed with a hook 91 the terminal of 25 which is seated in a recess 92 in the outer surface of the diagonally opposite corner casting 10. Similar tie rods 94 are also inserted through the openings 50 in the lower ends of diagonally opposite corner castings and adjusted by means of the nuts 96. These lower tie rods are covered by a layer of sand 98 laid upon the floor or ground surface upon which the fire-bricks 100 forming the floor of the combustion chamber are positioned. Outer edge portions of bricks 100 are inserted between the flanges 48 on the lower ends of the corner castings, the sand layer 98 being of such thickness that the bricks have reasonably close fitting contact with the upper flanges 48. The brick 100 at the front of the combustion chamber also extend between vertically spaced flanges 102 formed on the ash door frame 14.

The opposite side and rear walls of the combustion chamber consist of superposed courses of fire-brick 104, asbestos stripping 106 being interposed between the brick in adjacent courses and also between the opposed ends of the bricks in each course. Similar fire-brick 108 and interposed asbestos strips 110 are also inserted between the vertically spaced door frames 12 and 14. The angularly related walls 26 of the corner castings 10 provide abutment surfaces for the ends of the fire-brick, and asbestos strips 112 are also preferably interposed between these abutment surfaces and the fire-brick.

Facing sheets 114 of hard asbestos are inserted downwardly between the side and rear fire-brick walls and the flanges 20 of the corner castings 10. A similar asbestos facing sheet 116 also covers the outer sides of the fire-brick 108 with

its upper and lower edges disposed between the frames 12 and 14 and the fire-brick and its end edges extending between the flanges 20 of the front corner castings and the fire-brick 108. As will be seen in Figure 2 of the drawings, the top course of the fire-brick in the rear wall at their upper edge portions are engaged against the outer side of the depending flange 86 on the top casting 62.

The space between the rear top casting 62 and the charging door frame 14 at the top of the combustion chamber is closed by fire-brick 118 as shown in Figure 4. Thus, at each side of the casting 76 fire-bricks 118 are positioned with the outer ends of the bricks resting upon the upper courses of brick in the side walls of the combustion chamber while their inner ends and outer sides are supported by the flanges 84 on casting 76 flange 74 on casting 62 and the inner marginal edge of flange 58. Asbestos strips 120 are interposed between the edges of the bricks and casting 76 with similar asbestos strips 122 between the opposed side edges of the brick. When assembled in the manner just described, mere tightening of adjusting nuts 90 and 96 on the tie rods 88 and 94 will draw the diagonally opposed corner castings toward each other thereby clamping top casting assembly 16 and the combustion chamber brickwork tightly together so as to be securely held against relative displacement in a rigidly assembled unit. The asbestos stripping will be compressed under this clamping action thereby producing airtight combustion chamber walls.

All of the space above the fire-brick 118 and the castings 62 and 76 is filled with sand, as indicated at 124 in Figure 2 of the drawing up to the level of the upper edges of the facing sheets 114. A final top sheet 126 of hard asbestos having an opening to receive the outlet neck 68 is then applied with its forward edge disposed beneath bead 56 and its corners extending over the upper ends of the corner castings 10 and being secured thereto by screws 128 threaded into the openings 46 in the upper ends of said castings.

Preferably, in order to provide a smooth uninterrupted floor surface for the combustion chamber, a sand and cement mixture is applied over the fire-brick 100 and fills all crevices between said brick and between the adjacent surfaces of the side and rear wall brick 114 and the brick 100.

The charging door frame 12 at its lower end and at opposite sides of the door opening is provided with hinge lugs 139 upon which the charging door 132 is hingedly mounted by means of suitable pintles 134. The ash door frame 14 at one vertical side edge of the opening therein is also provided with hinge lugs 136 upon which the ash door 138 is hingedly mounted by the pintles 140. Preferably the charging door 132 at its upper end and centrally thereof is provided with an upwardly and inwardly projecting hook 131 receivable through an opening 133 in the door frame 12 when the door is moved to closed position. This hook has latching engagement with the lower edge of said opening and is effective to prevent the door being blown open by back draft through the combustion chamber. The doors 132 and 138 are provided with suitable opening handles 135 and 137 respectively and ash door 138 is also provided with latch structure 139 of conventional form.

It will, of course, be understood that the several parts of the incinerator structure as above described are properly dimensioned in accordance

with a predetermined combustion chamber capacity and that the number of fire-bricks which will be required may vary in accordance with the size of the combustion chamber.

All of the metal parts of the above described incinerator structure, including the necessary number of stove bolts, screws, hinge pintles and other fastening elements, together with asbestos sheets 114, 116 and 126, asbestos strip and cement for attaching the strip to the fire-brick, are shipped from the factory to the purchaser in the form of a compact knocked-down kit for erection either outdoors or indoors. In either case, it is necessary to locate the unit for connection to a suitable flue stack. When used indoors the house furnace flue is suitable but the incinerator should not be installed closer than 12 inches from any unprotected combustible wall. After laying out the incinerator kit and procuring the required number of fire-brick the incinerator may be rapidly erected in the following manner:

Having determined the exact location of the incinerator, the outside dimensions thereof are first outlined upon the basement floor or other support surface. Two corner castings 10, for the front corners are then selected. The door frames 12 and 14 are attached to the flanges 20 of these castings through openings 52 therein by means of stove bolts 54. These bolts fit loosely in the openings in flanges so to permit slight vertical adjustment to compensate for inaccuracies in brick dimensions and should be left comparatively loose until a later assembly step. The hard asbestos sheet 116 is then placed into position between the upper and lower door frame castings with the assembly laying face down on the basement floor. The necessary number of fire-brick 108 are now pressed firmly into place between the door castings 12 and 14 upon the asbestos facing sheet 116. This front assembly is then raised to a vertical position and the upper door frame 12 is forced downwardly so as to tightly clamp the bricks 108 between the two door frames. The stove bolts 54 are then tightened to secure the corner castings, the two door frames and the fire-brick in a rigidly assembled unit. Referring for the moment to Figures 2 and 6, the outer ends of brick 108 are disposed in overlapping relation to the sides of bosses 30 as shown. As a consequence, when the corner castings are drawn into final assembled position as hereinafter pointed out bosses 30 will prevent inward movement of brick 108 at their respective outer ends.

The top castings 62 and 76 are now rigidly connected by means of the stove bolts 78 and the bolt 80 is inserted through the opening, in the front end of casting 76, and a nut is started on the upper end thereof so that the bolt hangs loosely from said casting.

The top casting assembly is now loosely connected to the upper ends of the two remaining corner castings 10 by means of the bolts 40. The loose assembly is then set in position along the guide outlines on the supporting surface and the four tie rods 88 and 94 are inserted through the openings in the upper and lower ends of the diagonally opposed corner castings with bolt 88 slipped into the slot 82 in the flange 58 on the door frame 14. The diagonally crossed tie rods 88 and 94 extending through the openings in the upper and lower ends of the corner castings are drawn loosely together by tightening nut 90 by hand until the assembly approximately fits the outline markings on the floor.

The side and rear combustion chamber walls 75

are now installed by successively inserting the courses of fire-brick 104 between the corner castings 10 from the inner side thereof, the brick being disposed with their end faces in substantially abutting contact with the walls 20 of corner castings 10. After laying the first or bottom courses of the fire-brick directly upon the basement floor, the nuts on the two lower tie rods 94 are tightened until a close but still loose fitting assembly between the corner castings and lower course of fire-brick is obtained. A similar adjustment of the two top tie rods 88 is then made so that the four corner castings will be substantially parallel. A suitable gauge member is inserted between the fire-brick and the flanges 20 on the corner castings before tightening the tie rods 94 to assure sufficient clearance to receive the asbestos facing sheet 114.

After laying the first or bottom course of fire-brick for the side and rearwalls and tightening the tie rods as above explained, the remaining courses of fire-brick are successively positioned in similar manner in superposed relation between the corner castings with the asbestos strip between each course of brick and between the bricks in each course and between the bricks and the corner castings 10.

In order to assemble the last or top course of fire-brick it may be necessary to raise the top casting assembly 16 for which reason the bolts 40 and 80 were not tightened in connecting said assembly with the corner castings and flange 58. Preferably, a strip of asbestos is also interposed between the upper edge of the top 35 fire-bricks and the top casting 62. After laying the top course of fire-brick in the three walls the bolts 40 are then securely tightened. Referring to Figures 2 and 19 of the drawings, it will be seen that each end brick of each course 40 vertically centered with respect to a boss 30 of corner castings 10. As these end brick fit behind bosses 30 as heretofore described in connection with brick 108, it will be appreciated that inward movement of the side walls at each 45 corner is effectively prevented and proper clamping is materially aided.

The top fire-brick lining of the combustion chamber is now applied. Two of the brick 118 are first inserted at the rear end of casting 76 beneath the tie rods 88 and then moved forwardly under said tie rods over the rear edge of flange 58 on door frame 14 and into substantial abutting contact with the webs 60 of said frame, the inner ends of said bricks being supported on the side flanges 84 of the casting 76 and the other ends thereof on the top course of brick of the side walls of the combustion chamber. The rear brick 118 are then inserted with their rear edges resting upon the flange 74 of casting 62. Any gap or space between the brick and casting 62 and door frame 14 may be filled with asbestos strip. Strip 122 between the brick and 120 between the brick ends and casting 76 provide substantial seals.

After the assembly of the metal castings and fire-brick as above described, the side and rear sheets of hard asbestos 114 are then inserted with the smooth surfaces thereof facing outwardly. These facing sheets are slipped vertically downwardly between the fire-brick and the flanges 20 of the corner castings 10 and are of such length that with the lower edges thereof tightly bearing on the floor surface, their upper edges will then be substantially flush with the tops of the corner castings 10. The nuts 90 on

the four tie rods are then finally tightened against the corner castings to bind the several elements of the assembly into a rigid unit, after which the bolt 80 at the forward end of casting 16 is finally tightened.

The top sand filling 124 is now applied, and the cover sheet 126 of hard asbestos is then secured to the corner castings by screws 128.

Before placing the fire-brick floor of the combustion chamber, the bed of sand 98, preferably a mixture of sand and cement, is first laid upon the surface of the floor to a height covering the lower tie rods and to assure the fire-brick 100 being at the level of the ash door frame floor socket defined by webs 101 and flanges 102 just below the ash door opening. The upper surface of this bed is smoothly leveled off so that the forward edges of the front course of fire-brick 100 will slip between the flanges 102 into contact with the vertical edges of webs 101. The several courses of fire-bricks 100 cover the entire floor area between the lower courses of brick in the side and rear walls of the combustion chamber except for the intervening spaces which are filled either with loose sand, or a thin cement and water mixture. Finally, the charging door 132 and the ash door 138 are hingedly mounted upon the frames 12 and 14 respectively in the manner above described.

The elbow end of a flue pipe (not shown) is then connected to the upper end of the outlet neck 68 of the incinerator, the other end of said pipe being cemented in an opening provided in a side wall of the home furnace chimney or other suitable flue. However, if desired a T connection may be installed in the smoke outlet pipe from the furnace with which the flue pipe from the incinerator may be connected. This pipe, in either case is provided with a suitable damper for regulating the draft through the combustion chamber of the incinerator.

In event it is desired to ship the incinerator of this invention in assembled condition, the assembly steps just described are carried out at the factory, the assembly preferably being made upon a sheet metal floor laid on top of the lower tie rods. While the wall structure of the incinerator, due to the clamping action of the tie rods, is normally sufficiently rigid to withstand handling, it may be desirable to reinforce the side walls against inward collapse under external blows encountered in shipment. Such reinforcement can either be obtained by suitable structural modification of the frame castings as hereinafter described or, at less expense, by simple wooden shipping reinforcing inserts consisting of vertical risers 140a (dot dash lines Figure 2) overlapping the brick courses at their ends and cross wedge elements 141 (dot dash lines Figure 2) driven in place to hold risers 140a in place. These reinforcing strips can either be removed at the time of installing the incinerator or if desired may be left in place so as to be consumed by burning in use of the incinerator. While the wooden inserts are adequate in smaller sized incinerators where minimum expense is a prime consideration, additional structural frame elements may be provided if desired.

Such structural framing for incinerators of larger capacity, in which the combustion chamber walls have three or more fire-brick in each course, is provided as shown in Figures 20 to 23 of the drawing. This strengthening means

comprises spaced uprights each embodying a pair of rectangular sheet metal channel bars 142 arranged back to back and spot welded together. The lower ends of the side walls of said uprights are flared to receive the longitudinal side flanges of spaced base channel sections 144 and said base flanges are spot welded to the flared walls of the channel bars 142. The spacing between the uprights is determined in accordance with the length of the fire-brick so that as the brick courses are successively assembled the ends of the adjacent brick in each course will be slidably received within the oppositely facing channels of the bars 142. The bricks in the lowermost course are also supported on the base sections 144 between the side flanges thereof. Thus the chamber walls are materially strengthened and the bricks in each course are held in accurate alignment.

In case the complete incinerator unit, including the combustion chamber walls of fire-brick, is to be preassembled at the factory for shipment to the purchaser, the supporting sand layer 98 for the floor brick 100 of the combustion chamber as above described, is replaced by a floor plate 146 (Figure 22). At the same time the channels 142 and channel section 144 provide means to prevent the possible inward collapse of the fire-brick side walls, which might result from heavy shocks during shipment or rough handling in loading and unloading.

From the above it will be evident that when the upper and lower tie rods are tightened a very rigid assembly of the metal parts with the refractory fire-brick is obtained. As the fire-brick are securely held against relative displacement by the corner castings and channel bars 142 inward collapse of the combustion chamber walls is effectively precluded.

In the use of the incinerator, garbage and other waste material is intended to be wrapped in paper before placing in the combustion chamber. This paper wrapped garbage together with other combustible household refuse such as waste paper, cartons or the like is loaded into the incinerator and preferably permitted to accumulate until it reaches substantially the center of the charging door opening. The charge is then ignited at the top, care being taken to see that the smoke pipe damper is open to a sufficient extent to permit the free escape of products of combustion through the smoke outlet flue and into the furnace smoke stack. Air will be drawn into the combustion chamber in adequate volume through the openings 32 in the corner castings of the incinerator to support combustion and insure the free burning of the charge from the top down. The wet matter is effectively dehydrated by the heat of the adjacent burning layer or the induced circulation of air directed by openings inwardly and downwardly across and into the refuse material as heretofore described or both. Furthermore, the air entering the openings 32 above the burning layer is effective to assure combustion of generated gases and incompletely burned fly ash and relatively smokeless and odorless operation due to this secondary combustion. When the ashes have accumulated on the floor of the combustion chamber to substantially the center of the ash door opening, they should then be removed.

It has been found that, for the average residential installation where the incinerator is connected to a 6" or 8" diameter flue which also

serves the heating system of the home, the diameter of the air supply ports or openings 32 should not be less than $\frac{1}{4}$ " or greater than $\frac{5}{16}$ " in diameter. As is well known, the intensity of combustion increases with velocity of the air supplied to the combustion chamber. This velocity is proportional to the flue draft and dependent on the number and size of the air ports 32. The incinerator charge in an incinerator using the "air torch" principle as applied by this invention burns at a relatively high temperature. Accordingly not only the highly combustible portion of the charge but the normally non-combustible portion will be rapidly consumed, the brick walls will be highly heated and retain sufficient heat to materially aid dehydration of the wet material or garbage below the burning area to render it combustible.

By properly predetermining the number and diameter of the ports 32 in the corner castings in relation to the draft flue diameter and the size of the combustion chamber, adequate air will be supplied to support both primary and secondary combustion and the charge will be penetrated to the necessary depth to dehydrate the moisture laden content thereof and assure its complete combustion. The velocity of the incoming air streams determines the depth of penetration which may be controlled for incinerators of different sizes by flaring the inner ends of the ports or openings 32 so that air velocity is reduced and the air enters the chamber in a fan-shaped stream with correspondingly reduced penetration of the charge.

Since no grate is required, a charge receiving chamber of maximum capacity is obtained, the burning out of metal parts requiring replacement is avoided and economical, highly efficient operation is assured. Of course, it will be understood, that for incinerators of the larger sizes the air inlet ports 32 may be provided in corner castings 10 in greater number, larger size or both to assure sufficient air for high efficiency operation.

From the above description and the accompanying drawings it will be seen that this invention provides a household incinerator, which, with the exception of the fire-brick walls, comprises a minimum number of parts of simple and inexpensive structural form and comparatively light weight which can be compactly packaged and shipped to the purchaser in a suitable carton as a knocked-down kit. Following the above assembly instructions, the purchaser can rapidly and accurately assemble the several parts together with the fire-brick walls at the selected location to form a rugged, long life incinerator unit of neat appearance and high efficiency. As the several parts of the incinerator can be rapidly fabricated by conventional quantity production methods of manufacture, production cost is reduced to a minimum so that the purchase price thereof will be appreciably less than that of known incinerators now provided for the same job.

The invention may be embodied in other specific forms without departing from the spirit of essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by the United States Letters Patent is:

1. An incinerator construction kit comprising four preformed corner castings each having means to engage and position combustion chamber walls of fire-brick; preformed upper and lower charging and ash pit door frames respectively adapted to interconnect the upper and lower ends of a pair of said corner castings to form a front frame structure, hingedly mounted charging and ash pit doors on the respective frames; means adapted to secure said door frames between and to said pair of corner castings; a preformed top casting assembly; means adapted to secure said top casting assembly to the rear corner castings and to said upper door frame respectively; preformed non-combustible exterior finish panels adapted to fit between and close the back, side wall, and top areas between said corner castings, and the front side wall area between said door frames and said pair of corner castings; and preformed tie rods having means to adjustably connect diagonally opposite corner castings at their upper and lower ends whereby said opposed corner castings may be drawn inwardly with respect to each other along diagonally intersecting paths to tightly clamp and retain user assembled fire-brick walls together and in assembled relation to said exterior finish panels, said corner castings, and said door frames thereby forming a rigid incinerator unit.

2. A refuse incinerator comprising four corner castings each having abutment walls for engaging the vertical ends of mortarless fire-brick combustion walls; upper and lower charging and ash pit door frames secured to and respectively interconnecting the upper and lower ends of one pair of said castings to form a front frame section having vertically spaced charging and ash pit door openings separated by a panel opening adapted to be closed by a fire-brick wall panel; hinged doors respectively mounted in said door frames; a top casting assembly comprising a flue section secured to the upper ends of the other pair of corner castings and a tie section extending away from an edge of said flue section toward said upper charging door frame and connected to said door frame to locate said pairs of corner castings in fore and aft alignment; fire-brick walls extending downwardly from said top casting assembly between aligned fore and aft corner castings and between said other pair of corner castings, additional fire-brick walls in said panel opening and in the open spaces defined by the upper ends of said downwardly extending fire-brick walls, said upper door frame and said centrally disposed tie section and said flue section; and adjustable tie rods interconnecting the upper and lower ends of diagonally opposed pairs of said corner castings and adapted upon tightening thereof to draw each of said other pair of corner castings inwardly and toward its respective diagonally opposed corner casting to thereby draw the brickwork courses of said fire-brick walls into tight clamped engagement between said respective corner castings whereby a rigid incinerator unit is formed.

3. The incinerator defined by claim 2, in which each corner casting has an inwardly and longitudinally extending central portion providing oppositely facing abutment walls for the fire-brick of the respectively intersecting combustion chamber walls.

4. The incinerator defined by claim 2, wherein

13

said tie section is relatively narrow and said flue section, tie section, and charging door frame are provided with supporting flanges for fire-brick partially forming the top of the incinerator combustion chamber.

5. The incinerator defined by claim 4, in which said flue section is provided with an upstanding outlet neck for the connection of an incinerator smoke flue therewith.

6. The incinerator defined by claim 4 in which said corner castings are provided with longitudinally spaced air inlet openings arranged to inject air inwardly throughout the combustion space provided by said incinerator.

7. An incinerator comprising four corner castings each having means to engage and position combustion chamber walls of fire-brick; upper and lower charging and ash pit door frames respectively; means for securing said frames between and to the front pair of said corner castings; a pair of top castings; means for securing said top castings to each other and means for securing one of said top castings to the rear corner castings and the other top casting to said upper door frame; side flanges on said corner castings to overlap the outer sides of the combustion chamber walls; facing sheets of hard asbestos adapted to be disposed with their side edges between said walls and the side flanges of the corner castings; and tie rods for adjustably connecting diagonally opposite corner castings at their upper and lower ends to draw said corner castings into tight binding contact with the fire-brick walls and form a rigidly assembled incinerator unit.

8. The incinerator assembly defined in claim 7, together with an asbestos cover sheet for said top castings and means for securing said cover sheet to said corner castings.

9. An incinerator combustion chamber structure comprising front and rear corner castings; upper and lower charging and ash pit door frames; means securing said frames between and to the front corner castings; a front fire-brick wall between said door frames and front corner castings; side and rear fire-brick walls between said corner castings; longitudinally extending abutment surfaces on each of said corner castings disposed in angular relation to each other for contact with contiguous side edges of the adjacent fire-brick walls; and intersecting tie rods extending through the upper and lower ends of diagonally opposite corner castings and having adjusting nuts threaded thereon to draw said corner castings into tight abutting engagement with said contiguous side edges of the fire-brick walls thereby retaining said corner castings and fire-brick walls in rigidly assembled relation.

10. An incinerator combustion chamber structure as defined in claim 9, wherein the corner castings are provided with vertically spaced air injection openings; and means is provided for closing the top of the incinerator combustion chamber, including a casting assembly, and means securing said casting assembly to the charging door frame and to said rear corner castings.

11. An incinerator comprising front and rear corner castings; upper and lower charging and ash pit door frames, means securing said frames between and to the front corner castings; a front fire-brick wall between said door frames and front corner castings; side and rear fire-brick walls between said corner castings; longitudi-

14

nally extending abutment surfaces on each of said corner castings disposed in angular relation to each other for contact with contiguous side edges of the fire-brick walls; longitudinal flanges angularly disposed with respect to said abutment surfaces and overlapping the outer side edges of said fire-brick walls; hard asbestos facing sheets covering said walls with their opposite edges interposed between said flanges and said walls; and intersecting tie rods extending through the upper and lower ends of diagonally opposite corner castings having adjusting nuts threaded thereon and retaining said corner castings and fire-brick walls in rigidly assembled relation.

12. An incinerator as defined by claim 11, together with a top casting assembly having an outlet flue connecting neck and adapted to partially close the top of said incinerator; means securing said casting assembly to the charging door frame and to the rear corner castings; fire-brick closing the remainder of the top of the incinerator combustion chamber; and supporting means on the door frame and top casting assembly cooperating with the upper courses of said fire-brick walls to support said fire-brick.

13. An incinerator as defined by claim 12, wherein said top casting assembly includes a main casting extending between the rear corner castings and having a flue opening; and a relatively narrow tie casting centrally bridging the space between said main casting and the charging door frame.

14. In a household incinerator, front and rear corner castings; upper and lower charging and ash pit door frames; means securing said frames between and to the front corner castings; a front fire-brick wall between said door frames and front corner castings; side and rear fire-brick walls between said corner castings; longitudinally extending abutment surfaces on each of said corner castings disposed in angular relation to each other for contact with contiguous side edges of the fire-brick walls; longitudinal flanges along each abutment surface overlapping the outer sides of said fire-brick walls; hard asbestos facing sheets covering said walls with opposite edges thereof interposed between said flanges and said walls; a top casting assembly having an outlet flue connecting neck; means securing said assembly to the charging door frame and to the rear corner castings; fire-brick closing the top of the incinerator combustion chamber; supporting means on the door frame and top casting assembly acting together with the upper surface of said fire-brick walls to support said fire-brick; intersecting tie rods extending through the upper and lower ends of diagonally opposite corner castings and having adjusting nuts threaded thereon for retaining said corner castings and fire-brick walls in rigidly assembled relation; a cover sheet of hard asbestos secured to the upper end faces of said corner castings; and an insulating layer of sand between said cover sheet and said casting assembly and top fire-brick.

15. In a household incinerator as defined by claim 14, a combustion chamber floor comprising a layer of sand covering the lower tie rods and fire-brick superimposed thereon, said ash pit door frame and rear corner castings having inwardly projecting flanges for receiving the marginal fire-brick of said floor to determine the plane of said floor.

16. In an incinerator structure, angularly related side walls of refractory material forming a combustion chamber; a top closure for said cham-

ber having a flue connection therein; corner castings each having means in abutting contact with adjacent vertical edge portions of said walls and flanges overlapping the outer marginal edges of said walls; adjustable tie rods connecting diagonally opposite corner castings at their upper and lower ends and securing said castings and combustion chamber walls in a rigid assembly; and vertically spaced inwardly and downwardly inclined air injection openings in said corner castings adapted by reason of the draft through said flue connection to inject high velocity streams of combustion air inwardly and downwardly throughout the entire area of said combustion chamber.

17. The incinerator of claim 16 wherein each of said combustion chamber walls comprises a plurality of superposed courses of fire-brick having soft, asbestos, sealing strips disposed between the abutment faces of adjacent brick, between the vertical edge portions of said walls and the abutting means of said corner castings, and between the upper edges of said walls and said top closure whereby upon adjustment of said tie rods the corner castings and the individual brick of the combustion walls are embedded in said sealing strips thereby providing a gas tight combustion chamber.

18. The combination defined in claim 16 wherein said air injection openings at their inner ends are defined by inwardly directed, vertically spaced bosses of a length sufficient to overlap the inner vertical edges of the adjacent intersecting refractory walls thereby preventing inward movement of the opposite wall ends during tightening of said tie rods.

19. In an incinerator structure as defined in claim 16 wherein each of said combustion chamber walls comprises a plurality of superposed courses of fire-brick with at least two bricks in each course, reinforcing uprights each comprising rigidly connected oppositely facing channel bars in which the opposed ends of the fire-brick in each course are respectively engaged.

20. In an incinerator structure as defined in

claim 19, a base member welded to the lower end of each upright and comprising a channel bar section in which the lower edge of opposed ends of adjacent fire-brick in the bottom course are seated.

21. In an incinerator structure, angularly related walls each comprising superposed courses of fire-brick with at least two bricks in each course and forming a combustion chamber; corner castings each having means in abutting contact with adjacent vertical edge portions of said walls; reinforcing uprights each comprising rigidly connected oppositely facing channel bars in which opposed ends of the adjacent fire-brick in one of said walls is engaged; certain of said corner castings being provided with vertically spaced air injection openings; tie rods connecting diagonally opposite corner castings at their upper and lower ends and retaining said castings and combustion chamber walls in a rigid assembly; a floor plate directly supported upon the lower tie rods; and a fire-brick floor for the combustion chamber supported upon said floor plate.

22. In an incinerator structure as defined in claim 21, said upright channel bars having the lower ends of their side flanges bowed outwardly to receive there between channel footings extending in opposite directions a distance less than a single brick length, and a bed of asbestos-cement grout for the floor brick covering the floor plate.
